FILM THICKNESS GAUGE

Ervin J. Michalak, San Francisco, Calif.

Application November 30, 1953, Serial No. 27,838

Term of patent 14 years

(Cl. D52—6)

FIG. 1

FIG. 2

FIG. 3

FIG. 4

Fig. 1 is a perspective view of a film thickness gauge, showing my new design.

Fig. 2 is a top plan view of said gauge.

Fig. 3 is an end view of said gauge, and

Fig. 4 is a side view of the gauge viewing toward the respective corners of the end flanges.

I claim:

The ornamental design for a film thickness gauge, as shown.
